CLAIM

I claim the ornamental design for a shoe, as shown and described.

DESCRIPTION

FIG. 1 is a rear bottom perspective view of a shoe, showing my new design;

FIG. 2 is a front bottom perspective view thereof; and,

FIG. 3 is a bottom view thereof.

The dot-dash broken lines represent boundaries of the claimed design and form no part of the claimed design. The broken lines depicting the remainder of the shoe show features that form no part of the claimed design.
